ABSTRACT

An optoelectronic circuit for receiving a variable voltage containing alternating increasing and decreasing phases, the optoelectronic circuit including a plurality of groups of light-emitting diodes and a switching device for allowing or interrupting the circulation of a current through each group, the switching device also being suitable for detecting whether said variable voltage is supplied by a dimmer.

OPTOELECTRONIC CIRCUIT COMPRISING
LIGHT-EMITTING DIODESCROSS-REFERENCE TO RELATED
APPLICATIONS

This application is the national phase of International Application No. PCT/FR2015/053757, filed on Dec. 24, 2015, which claims priority to French Application No. 14/63416, filed on Dec. 30, 2014, which applications are incorporated herein by reference to the maximum extent allowable.

BACKGROUND

The present description relates to an optoelectronic circuit, particularly to an optoelectronic circuit comprising light-emitting diodes.

DISCUSSION OF THE RELATED ART

An optoelectronic circuit, especially used to form lighting, may be connected to a source of an AC voltage, for example, the sinusoidal voltage of the mains. To modify the luminous power supplied by the lighting circuit, it is known to place a dimmer between the source of the sinusoidal voltage and the optoelectronic circuit. There exist several types of dimmers, particularly leading edge dimmers and trailing edge dimmers.

It may be desirable to use a lighting circuit comprising light-emitting diodes. A disadvantage is that dimmers have generally been designed to operate with incandescent lamp lighting circuits and may not operate properly when they are connected to an optoelectronic circuit comprising light-emitting diodes.

SUMMARY

An object of an embodiment is to overcome all or part of the disadvantages of the previously-described optoelectronic circuits comprising light-emitting diodes powered with an AC voltage.

Another object of an embodiment is to allow a proper operation of a dimmer placed between the AC voltage source and the optoelectronic circuit.

Thus, an embodiment provides an optoelectronic circuit intended to receive a variable voltage containing an alternation of rising and falling phases, the optoelectronic circuit comprising a plurality of light-emitting diode assemblies and a switching device capable of allowing or of interrupting the flowing of a current in each assembly, the switching device being further capable of detecting whether said variable voltage is supplied by a dimmer.

According to an embodiment, the switching device is capable of connecting the assemblies of light-emitting diodes according to a plurality of connection configurations successively according to a first order during each rising phase of the variable voltage in the absence of a dimmer and a second order during each falling phase of the variable voltage in the absence of a dimmer, the switching device being further capable of detecting the presence of the dimmer when the duration of at least one connection configuration is shorter than a duration threshold and/or when at least two connection configurations follow each other according to a third order different from the first order and from the second order.

2

According to an embodiment, the duration threshold depends on said connection configuration.

According to an embodiment, the switching device comprises at least one switch for each assembly of light-emitting diodes, the switching device being capable of transmitting binary control signals for the turning off or the turning on of the switches according to said connection configurations, the switching device being, further, capable of determining whether the duration between the successive switching times of one of at least two control signals of two successive connection configurations is shorter than said duration threshold.

According to an embodiment, the switching device comprises, for each assembly, a comparison unit capable of comparing the voltage at one of the terminals of the assembly, and/or a voltage depending on said voltage at one of the terminals of the assembly, with at least one first voltage threshold and possibly with a second voltage threshold and a control unit connected to the comparison units and capable, during each rising phase, of interrupting the flowing of a current in each assembly from among certain assemblies of the plurality of assemblies when said voltage of said assembly rises above the second voltage threshold or when said voltage of the assembly, adjacent to said assembly and conducting the current, rises above the first voltage threshold and, during each falling phase, of controlling the flowing of a current in each assembly from among certain assemblies of the plurality of assemblies when said voltage of the assembly, adjacent to said assembly and conducting the current, decreases below the first voltage threshold.

According to an embodiment, the switching device is capable of detecting the presence of the dimmer when, for at least two assemblies, the voltages associated with the two assemblies rise above the first voltage threshold or the second voltage threshold or fall below the first voltage threshold within a duration shorter than said duration threshold.

According to an embodiment, the optoelectronic circuit comprises a current source and, for each assembly, a switch connecting the current source to said terminal of said assembly, the control unit being capable, for each assembly from among certain assemblies of the plurality of assemblies, of controlling the turning on of the switch associated with said assembly when said voltage of the assembly, adjacent to said assembly and conducting the current, falls below the first voltage threshold in each falling phase.

According to an embodiment, the switching device is further capable of detecting whether the variable voltage is supplied by a leading edge dimmer or a trailing edge dimmer.

According to an embodiment, the switching device is further capable of determining that the variable voltage is supplied by a leading edge dimmer when the duration of at least one connection configuration is shorter than a duration threshold during at least a rising phase of the variable voltage and/or when at least two connection configurations follow each other according to a fourth order different from the first order during at least a rising phase of the variable voltage and the switching device is, further, capable of determining that the variable voltage is supplied by a trailing edge dimmer when the duration of at least one connection configuration is shorter than a duration threshold during at least one falling phase of the variable voltage and/or when at least two connection configurations follow each other according to a fifth order different from the second order during at least one falling phase of the variable voltage.

According to an embodiment, the switching device is capable of at least temporarily decreasing the input impedance of the optoelectronic circuit when a dimmer is detected.

According to an embodiment, the switching device is capable of having a constant current flow through the optoelectronic circuit when a dimmer is detected.

BRIEF DESCRIPTION OF THE DRAWINGS

The foregoing and other features and advantages will be discussed in detail in the following non-limiting description of dedicated embodiments in connection with the accompanying drawings, among which:

FIG. 1 is an electric diagram of an example of an optoelectronic circuit connected to a source of a sinusoidal voltage by a dimmer;

FIGS. 2 and 3 are timing diagrams of the voltage supplied by the dimmer of FIG. 1 respectively in the case of a leading edge dimmer and of a trailing edge dimmer;

FIG. 4 is an electric diagram of an example of an optoelectronic circuit comprising light-emitting diodes capable of being connected to a source of a sinusoidal voltage;

FIG. 5 is a timing diagram of the power supply current and voltage of the light-emitting diodes of the optoelectronic circuit of FIG. 4;

FIG. 6 is an electric diagram of an example of an optoelectronic circuit comprising light-emitting diodes comprising a light-emitting diode switching device;

FIG. 7 is a timing diagram of signals of the optoelectronic circuit of FIG. 6;

FIGS. 8 and 9 are timing diagrams of signals of the optoelectronic circuit of FIG. 6 when it is connected to a leading edge and to a trailing edge dimmer;

FIG. 10 shows, in the form of a block diagram, an embodiment of a method of detecting the presence or the absence of a dimmer;

FIG. 11 partially and schematically shows an embodiment of a unit for detecting the presence or the absence of a dimmer;

FIG. 12 is an electric diagram of another example of an optoelectronic circuit comprising light-emitting diodes comprising a light-emitting diode switching device;

FIG. 13 schematically shows an embodiment of a control unit of a light-emitting diode switching device;

FIG. 14 shows, in the form of a block diagram, an embodiment of a method of controlling a light-emitting diode switching device;

FIG. 15 is an electric diagram of an embodiment of an optoelectronic circuit comprising light-emitting diodes, comprising a dimmer detection device;

FIG. 16 shows a more detailed embodiment of an optoelectronic circuit comprising light-emitting diodes, comprising a dimmer detection device;

FIGS. 17 and 18 are more detailed electric diagrams of embodiments of portions of the optoelectronic circuit of FIG. 16;

FIG. 19 is a timing diagram of voltages of the optoelectronic circuit of FIG. 16;

FIG. 20 shows an electric diagram of another embodiment of an optoelectronic circuit comprising light-emitting diodes comprising a dimmer detection device; and

FIGS. 21 and 22 are drawings respectively similar to FIGS. 17 and 18 and show electric diagrams of more detailed embodiments of portions of the optoelectronic circuit of FIG. 20.

DETAILED DESCRIPTION

For clarity, the same elements have been designated with the same reference numerals in the various drawings and, further, the various drawings are not to scale. In the following description, unless otherwise indicated, terms "substantially", "approximately", and "in the order of" mean to within 10%, preferably to within 5%.

FIG. 1 very schematically shows an electronic system 1 comprising a source 2 of an AC voltage V_{SOURCE} , for example, a sinusoidal voltage, a dimmer 5 receiving AC voltage V_{SOURCE} and supplying a modified AC voltage V_{IN} , and an optoelectronic circuit 10 comprising input terminals IN_1 and IN_2 having AC voltage V_{IN} applied therebetween.

As an example, input voltage V_{SOURCE} may be a sinusoidal voltage having a frequency, for example, in the range from 10 Hz to 1 MHz. Voltage V_{SOURCE} for example corresponds to the mains voltage.

Optoelectronic circuit 10 is capable of supplying a light signal having its luminous power depending, in particular, on voltage V_{IN} . Dimmer 5 may be a phase cut dimmer comprising an electronic switch having a conduction time limited to a fraction of period T of voltage V_{SOURCE} .

FIG. 2 shows an example of a curve of the variation of voltage V_{IN} when source voltage V_{SOURCE} is sinusoidal with a period T and when dimmer 5 is a leading edge dimmer. Voltage V_{IN} follows signal V_{SOURCE} except for a time period T' at the beginning of each positive and negative sine wave arc during which voltage V_{IN} is substantially zero. Leading edge dimmers may be formed with triacs.

FIG. 3 shows an example of a curve of the variation of voltage V_{IN} when source voltage V_{SOURCE} is sinusoidal with a period T and when dimmer 5 is a trailing edge dimmer. Voltage V_{IN} follows signal V_{SOURCE} except for a time period T'' at the end of each positive and negative sine wave arc during which voltage V_{IN} is substantially zero. Trailing edge dimmers may be formed with MOS transistors.

Ratio α of time period T' or T'' to half-period $T/2$ of sinusoidal signal V_{SOURCE} is called firing angle of dimmer 5. A leading edge or trailing edge dimmer may comprise a variable resistance, which enables to modify firing angle α .

It may be desirable to use light-emitting diodes to form optoelectronic circuit 10.

FIG. 4 shows an example of an optoelectronic circuit 10 comprising light-emitting diodes. Optoelectronic circuit 10 comprises a rectifying circuit 12 comprising a diode bridge 14, receiving voltage V_{IN} and supplying a rectified voltage V_{ALIM} which powers light-emitting diodes 16, for example, series-assembled with a resistor 15. Call I_{ALIM} the current flowing through light-emitting diodes 16.

FIG. 5 is a timing diagram of power supply voltage V_{ALIM} and of power supply current I_{ALIM} for an example where AC voltage V_{IN} corresponds to a sinusoidal voltage. When voltage V_{ALIM} is greater than the sum of the threshold voltages of light-emitting diodes 16, light-emitting diodes 16 become conductive. Power supply current I_{ALIM} then follows power supply voltage V_{ALIM} . There thus is an alternation of phases OFF without light emission and of light-emission phases ON.

A disadvantage is that dimmers 5 available for sale have generally been designed to operate with incandescent lamp illumination circuits and may not operate properly when they are connected to an optoelectronic circuit comprising light-emitting diodes. As an example, the proper operation of certain dimmers may require for the input impedance of optoelectronic circuit 10 seen by dimmer 5 to be low when voltage V_{IN} is close to 0 V. However, in phases OFF when

no light is emitted, light-emitting diodes **16** are non-conductive and optoelectronic circuit **10** then has a high input impedance, which may disturb the operation of dimmer **5**.

According to an embodiment, the optoelectronic circuit comprises a device for detecting the presence or the absence of a dimmer connected to the input terminals of the optoelectronic circuit. According to an embodiment, the optoelectronic circuit further comprises a device capable of modifying certain properties of the optoelectronic circuit when a dimmer is detected, particularly to decrease the input impedance seen by the dimmer when the optoelectronic circuit is powered with a low voltage, to avoid disturbing the operation of the dimmer.

There exist optoelectronic circuits comprising a light-emitting diode switching circuit capable of progressively increasing the number of light-emitting diodes receiving power supply voltage V_{ALIM} during a rising phase of the power supply voltage and of progressively decreasing the number of light-emitting diodes receiving power supply voltage V_{ALIM} during a falling phase of the power supply voltage. The switching circuit is generally capable of short-circuiting a variable number of light-emitting diodes according to the variation of voltage V_{ALIM} . This enables to decrease the duration of each phase OFF with no light emission.

FIG. 6 shows an electric diagram of an example of an optoelectronic circuit **20** comprising a light-emitting diode switching device. The elements of optoelectronic circuit **20** common with optoelectronic circuit **10** are designated with the same reference numerals. In particular, the optoelectronic circuit comprises rectifying circuit **12** receiving power supply voltage V_{IN} between terminals IN_1 and IN_2 and supplying rectified voltage V_{ALIM} between nodes A_1 and A_2 . As a variation, circuit **20** may directly receive a rectified voltage, and it is then possible for the rectifying circuit not to be present.

Optoelectronic circuit **20** comprises N series-connected assemblies of elementary light-emitting diodes, called general light-emitting diodes D_i in the following description, where i is an integer in the range from 1 to N and where N is an integer in the range from 2 to 200. Each general light-emitting diode D_1 to D_N comprises at least one elementary light-emitting diode and is preferably formed of the series and/or parallel assembly of at least two elementary light-emitting diodes. In the present example, the N general light-emitting diodes D_i are series-connected, the cathode of general light-emitting diode D_i being coupled to the anode of general light-emitting diode D_{i+1} , for i varying from 1 to $N-1$. The anode of general light-emitting diode D_1 is coupled to node A_1 . General light-emitting diodes D_i , with i varying from 1 to N , may comprise the same number of elementary light-emitting diodes or different numbers of elementary light-emitting diodes.

Optoelectronic circuit **20** comprises a current source **22** having a terminal connected to node A_2 and having its other terminal connected to a node A_3 . Current source **22** may correspond to a resistor. Circuit **20** comprises a light-emitting diode switching device **24**. As an example, device **24** comprises N controllable switches SW_1 to SW_N . Each switch SW_i , with i varying from 1 to N , is assembled between node A_3 and the cathode of general light-emitting diode D_i . Each switch SW_i , with i varying from 1 to N , is controlled by a signal S_i supplied by a control unit **26**. Control unit **26** may be totally or partly formed by a dedicated circuit or may comprise a microprocessor or a microcontroller capable of executing a series of instructions stored in a memory. As an example, signal S_i is a binary

signal and switch SW_i is off when signal S_i is in a first state, for example, the low state, and switch SW_i is on when signal S_i is in a second state, for example, the high state.

Optoelectronic circuit **20** comprises one or a plurality of sensors connected to control unit **26**. It may be a single sensor, for example, a sensor capable of measuring voltage V_{ALIM} or the current flowing between terminals IN_1 and IN_2 , or a plurality of sensors, where each sensor may be associated with a general light-emitting diode D_i . As an example, a single sensor **28** has been shown in FIG. 6.

Control unit **26** is capable of controlling the turning on or the turning off of switches SW_i , with i varying from 1 to $N-1$, according to the value of voltage V_{ALIM} according to a sequence based on the measurement of a physical parameter, for example, at least one current or one voltage. As an example, the turning off and the turning on of switches SW_i may be controlled by control unit **26** based on the signals supplied by sensor **28** or the sensors. As a variation, the turning off and the turning on of switch SW_i may be controlled from the measurement of the voltage at the cathode of each general light-emitting diode D_i . As a variation, the turning off and the turning on of switch SW_i may be controlled from the measurement of voltage V_{ALIM} or the measurement of the voltage at the cathode of each general light-emitting diode D_i . The number of switches SW_1 to SW_N may vary according to the turn-off and turn-on sequence implemented by control unit **26**. As an example, switch SW_N may not be present.

FIG. 7 shows curves of the variation of signals S_i , with i varying from 1 to $N-1$, N being equal to 4 during a cycle of voltage V_{ALIM} in the case where voltage V_{IN} is a sinusoidal voltage for an example of a switching method implemented by switching device **24**. As an example, at the beginning of a rising phase of voltage V_{ALIM} , signals S_i , with i varying from 1 to $N-1$, are initially at "1" so that switches SW_i are on. Switches SW_1 , SW_2 , and SW_3 are successively turned off at times t_1 , t_2 , and t_3 along the rise of voltage V_{ALIM} so that general light-emitting diodes D_2 , D_3 , and D_4 are successively powered with current. During a falling phase of voltage V_{ALIM} , switches SW_3 , SW_2 , and SW_1 are successively turned on at times t'_1 , t'_2 , and t'_3 to successively short-circuit general light-emitting diodes D_4 , D_3 , and D_2 .

According to an embodiment, the light-emitting diode switching device is, further, capable of detecting the presence or the absence of a dimmer connected to terminals IN_1 and IN_2 . The function of detecting the presence or the absence of a dimmer may advantageously be implemented with the light-emitting diode switching device already equipping certain optoelectronic circuits comprising light-emitting diodes with few modifications. An embodiment of a method of detecting the presence or the absence of a dimmer will be described with an optoelectronic circuit comprising light-emitting diodes **20**, comprising a light-emitting diode switching device **24** having the structure shown in FIG. 6. It should however be clear that the method of detecting the presence or the absence of a dimmer may be implemented with other structures of light-emitting diode switching devices, particularly light-emitting diode switching devices described in patent applications US 2012/0056559, US 2008/0211421, US 2011/0273102, and U.S. Pat. No. 7,081,722.

According to an embodiment, control unit **26** is capable of comparing at least some of switching times t_i , that is, of turning on and/or off, switches SW_i , with i varying from 1 to N , during a rising phase of voltage V_{ALIM} and at least some of switching times t'_i of switches SW_i , with i varying from 1 to N , during a falling phase of voltage V_{ALIM} . In the

absence of a dimmer, voltage V_{ALIM} varies progressively during each cycle, switching times t_i , with i varying from 1 to N , being then different during each cycle and switching times t'_i being also different during each cycle. When a dimmer is present, each cycle comprises a first phase, at the beginning or at the end of a cycle, during which voltage V_{ALIM} is substantially at 0 V, and a second phase during which voltage V_{ALIM} substantially follows voltage V_{IN} , shifted by the threshold voltages of diodes 14 of rectifying bridge 12. There thus is, during each cycle, an abrupt increase or an abrupt decrease of voltage V_{ALIM} at the transition between the first and second phases. This causes the simultaneous switching of at least two switches during each cycle.

In the previously-described embodiment, a switching time t_i or t'_i corresponds to a time when a switch is turned off or on, that is, at a time when a binary signal S_i for controlling a switch SW_i switches. More generally, a switching time corresponds to a change in the configuration of the connection of light-emitting diode assemblies D_i , which causes a modification of the electric path followed by the current between terminals IN_1 and IN_2 . A switching time can then correspond to a switching time of a binary signal supplied by a sensor to control unit 36 and/or to a switching time of a binary signal supplied by control unit 26 to a switch. In particular, when the switching times correspond to the switchings of signals supplied by sensors, according to the control method implemented by control unit 26, the fact for switching times to be simultaneous may not cause the simultaneous turning on of a plurality of switches or the simultaneous turning off of a plurality of switches. In the following description, turn-off time t_i will designate a switching time in a rising phase of voltage V_{ALIM} and turn-on time t'_i will designate a switching time in a falling phase of voltage V_{ALIM} .

FIGS. 8 and 9 illustrate the principle of the detection of the presence or of the absence of a dimmer.

FIG. 8 is a drawing similar to FIG. 7 in the case where optoelectronic circuit 20 is connected to a leading edge dimmer with a firing angle α equal to 0.5. As appears in this drawing, turn-off times t_1 , t_2 , and t_3 of switches SW_1 , SW_2 , and SW_3 are substantially simultaneous. When firing angle α is different from 0.5, the number of switches which are simultaneously turned off may be smaller than $N-1$.

FIG. 9 is a drawing similar to FIG. 7 in the case where optoelectronic circuit 20 is connected to a trailing edge dimmer with a firing angle α equal to 0.5. As appears in this drawing, turn-on times t'_1 , t'_2 , and t'_3 of switches SW_1 , SW_2 , and SW_3 are substantially simultaneous. When firing angle α is different from 0.5, the number of switches which are simultaneously turned on may be smaller than $N-1$.

FIG. 10 shows, in the form of a block diagram, an embodiment of a method of detecting the presence or the absence of a dimmer which may be used by control unit 26.

At step 40, control unit 26 determines switching times t_i , t'_i of switching device 24 during a cycle of voltage V_{ALIM} . The method carries on at step 42.

At step 42, control unit 26 compares with one another at least some of turn-off times t_i of switches SW_i and compares with one another at least some of turn-off times t'_i of switches SW_i . As an example, control unit 26 may compare turn-off times t_i and t_{i+1} and turn-on times t'_i and t'_{i+1} . Control unit 26 may further compare at least some of turn-off times t_i with at least some of turn-on times t'_i . The method carries on at step 44.

At step 44, according to the result of the comparison at step 42, control unit 26 determines whether a dimmer is

present. If at least two turn-off times t_i are close or substantially simultaneous or if at least two turn-on times t'_i are close or substantially simultaneous, this means that a dimmer is present. "Close" means that the duration between the two switching times t_i and t_{i+1} or t'_i and t'_{i+1} is smaller than a duration threshold which may depend on the considered time t_i or t'_i . In the case where turn-off times t_i are not close or simultaneous and where, further, turn-on times t_i are not close or simultaneous, this means that there is no dimmer.

10 Steps 40, 42, and 44 may be at last partly carried out.

According to an embodiment, at step 44, control unit 26 is further capable of determining whether the detected dimmer is a leading edge dimmer or a trailing edge dimmer according to whether the close or simultaneous switching times are switch turn-on times or switch turn-off times. In 15 the example of a switching method illustrated in FIGS. 8 and 9, a leading edge dimmer is detected when the simultaneous switching times are turn-off times and a trailing edge dimmer is detected when the simultaneous switching times are 20 turn-on times.

According to an embodiment, at step 44, control unit 26 is further capable of determining firing angle α of the dimmer. This may in particular be performed from the determination of the time period, during a cycle of voltage 25 V_{ALIM} , between the switching time (turn-on or turn-off) of a switch, which simultaneously occurs with other switching times in a rising or falling phase of voltage V_{ALIM} , and the switching time of this same switch which occurs in the other phase, falling or rising, of voltage V_{ALIM} .

30 FIG. 11 shows an embodiment of a unit 45 for detecting the presence or the absence of a dimmer capable of implementing the method previously described in relation with FIG. 10. Detection unit 45 may be part of control unit 26.

According to the present embodiment, unit 45 receives at 35 least N signals Qen_i , with i varying from 1 to N , each signal Qen_i being representative of a change of configuration of switching device 24 during a rising phase of signal V_{ALIM} . According to an embodiment, signal Qen_i may correspond to the complementary of control signal S_i of switch SW_i . Unit 40 45 further comprises $N-1$ timers 46_i (Timer), with i varying from 1 to $N-1$. Each timer 46_i receives signal Qen_i and is activated when signal Qen_i switches from "0" to "1". Each timer 46_i supplies a binary signal Een_i , which switches state 45 when a predetermined duration is reached after the activation of timer 46_i . The predetermined duration may depend on the considered timer 46_i . Unit 45 further comprises $N-1$ "AND" logic gates 47_i , with i varying from 1 to $N-1$. Each logic gate 47_i receives signal Een_i and signal Qen_{i+1} and supplies a binary signal $LEdetect_i$ at "1" when signal Een_i and Qen_{i+1} are simultaneously at "1". Unit 45 further comprises an "OR" logic gate 48 receiving signals $LEdetect_i$, with i varying from 1 to $N-1$, and supplying a binary signal $LEdetect$ which, for example, is set to "1" when at least one of signals $LEdetect_i$, with i varying from 1 to $N-1$, is at "1" and which is set to "0" when all signals $LEdetect_i$, with i varying from 1 to $N-1$, are at "0".

When the duration between at least two turn-off times t_i and t_{i+1} is shorter than the duration measured by timer 46_i , signal $LEdetect_i$ is set to "1" and signal $LEdetect$ is set to "1". This means the detection of a leading edge dimmer.

According to the present embodiment, unit 45 receives at least N signals $Qdis_i$, with i varying from 1 to N , each signal $Qdis_i$ being representative of a change of configuration of switching device 24 during a falling phase of signal V_{ALIM} . 60 According to an embodiment, signal $Qdis_i$ may correspond to control signal S_i of switch SW_i . Unit 45 further comprises $N-1$ timers 49_i , with i varying from 2 to N . Each timer 49_i

receives signal Q_{dis_i} and is activated when signal Q_{dis_i} switches from "0" to "1". Each timer 49_i supplies a signal E_{dis_i} , which switches state when a predetermined duration is reached after the activation of timer 49_i . The predetermined duration may depend on the considered timer 49_i . Unit 45 further comprises N-1 "AND" logic gates 50_i , with i varying from 2 to N. Each logic gate 50_i receives signal E_{dis_i} and signal $Q_{dis_{i-1}}$ and supplies a binary signal TE_{detect_i} at "1" when signal E_i and $Q_{dis_{i+1}}$ are simultaneously at "1". Unit 45 further comprises an "OR" logic gate 51 receiving signals TE_{detect_i} , with i varying from 2 to N, and supplying a binary signal TE_{detect} which, for example, is set to "1" when at least one of signals TE_{detect_i} , with i varying from 2 to N, is at "1", and which is set to "0" when all signals TE_{detect_i} , with i varying from 2 to N, are at "0". A trailing edge dimmer is detected when signal TE_{detect} is at "1".

When the duration between at least two turn-on times t_i and t_{i+1} is shorter than the duration measured by timer 49_{i+1} , signal $TE_{detect_{i+1}}$ is set to "1" and signal TE_{detect} is set to "1". This means the detection of a trailing edge dimmer.

According to an embodiment, the duration measured by each timer 46_i or 49_i is the same for each timer 46_i or 49_i . According to an embodiment, the duration measured by each timer 46_i or 49_i depends on the timer 46_i or 49_i . According to an embodiment, the duration measured by each timer 46_i or 49_i is smaller than the theoretical duration expected between times t_i and t_{i+1} or between times t_i and t_{i+1} in the absence of a dimmer. The theoretical duration may be determined from the knowledge of the maximum amplitude and frequency of signal V_{ALIM} and on the number of light-emitting diodes of each light-emitting diode assembly D_i .

The embodiment shown in FIG. 11 may advantageously be achieved by a digital circuit or an analog circuit. In the case of a digital circuit, timer 46_i , 49_i may be rated by a clock signal. In the case of an analog circuit, timer 46_i , 49_i may comprise a capacitor charged at constant current.

According to another embodiment, the unit for detecting the presence or the absence of a dimmer is capable of storing the successive times t_i and t'_i . This enables, advantageously at previously-described step 44, to compare more than two turn-off times t_i , more than two turn-on times t'_i and/or turn-off times t_i with turn-on times t'_i . To store successive times t_i and t'_i , a timer which is for example activated at switching time t_1 and stopped at switching time t'_1 may be used. The duration between times t_1 and t'_1 is representative, in the absence of a dimmer, of the period of voltage V_{ALIM} .

Advantageously, the previously-described embodiments of methods of detecting the presence or the absence of a dimmer may be implemented with known optoelectronic circuits comprising a light-emitting diode switching device, with no other modification than the addition of the detection unit.

FIG. 12 corresponds to FIG. 5 of U.S. Pat. No. 7,081,722 which is herein incorporated by reference. FIG. 12 shows an embodiment of an optoelectronic circuit comprising a light-emitting diode switching device with which the previously-described embodiments of the method of detecting the presence or the absence of a dimmer may be implemented. Indeed, signals Q_{en_i} , previously described in relation with FIG. 11, may correspond to the complementaries of the signals for controlling the gates of MOS transistors Q_i , with i varying from 1 to 4, of FIG. 12 and signals Q_{dis_i} , previously-described in relation with FIG. 11, may correspond to the signals for controlling the gates of MOS transistors Q_i , with i varying from 1 to 4.

FIG. 13 shows an embodiment of control unit 26 of optoelectronic circuit 20. Control unit 26 comprises a processing unit 52 and a unit 53 for detecting the presence or the absence of a dimmer. Processing unit 52 receives signals and/or signals Q_{en_i} and is capable of supplying control signals S_i , with i varying from 1 to N. Detection unit 53 receives signals Q_{en_i} and/or signals Q_{dis_i} and supplies signals LE_{detect} and TE_{detect} to processing unit 52.

FIG. 14 shows, in the form of a block diagram, where an embodiment of a method of controlling a light-emitting diode switching device capable of being implemented by control unit 26 shown in FIG. 13. The control method comprises previously-described steps 40, 42, 44. At step 44, if detection unit 53 has detected the presence of a dimmer, the method carries on at step 54. At step 44, if detection unit 53 has not detected the presence of a dimmer, the method carries on at step 55.

At step 54, processing unit 52 may control a first operating mode adapted to the presence of a dimmer. According to an embodiment, the first operating mode comprises decreasing the input impedance of the optoelectronic circuit seen by the dimmer when no light-emitting diode is conducting. According to an embodiment, a first operating mode comprises maintaining a current flowing between terminals IN_1 and IN_2 permanently above a current threshold which may be adapted to the proper operation of the dimmer. According to an embodiment, a first operating mode comprises permanently maintaining a constant current between terminals IN_1 and IN_2 . The method carries on at step 40.

At step 55, control unit 26 may control a second adapted operating mode when a dimmer is not present, which for example corresponds to the normal operating mode of switching device 22. The method carries on at step 40.

Steps 40 to 55 may be implemented for each cycle of voltage V_{ALIM} , one cycle out of two, one cycle out of ten, etc.

According to an embodiment, at the start, the optoelectronic circuit may operate according to the first operating mode before the first implementation of the method of detecting the presence or the absence of a dimmer. Thereby, if the presence of a dimmer is confirmed at step 44, the optoelectronic circuit is already in the first operating mode. Risks of a poor operation of the dimmer at the start are thus advantageously avoided.

The first operating mode implemented at step 54 may depend on the type of detected dimmer. As an example, in the first operating mode, when a current flowing between terminals IN_1 and IN_2 is permanently maintained above a current threshold, the current threshold may depend on the type of detected dimmer.

The first operating mode implemented at step 54 may depend on the determined firing angle α . As an example, in the first embodiment, when a constant current is maintained between terminals IN_1 and IN_2 , the current level may depend on the determined firing angle α .

FIG. 15 shows an embodiment of an optoelectronic circuit 56 comprising a light-emitting diode switching device 57 capable of detecting the presence or the absence of a dimmer connected to terminals IN_1 and IN_2 and further capable, in the first operating mode, of decreasing the input impedance of optoelectronic circuit 56 seen by the dimmer. Optoelectronic circuit 56 comprises all the elements of optoelectronic circuit 20 shown in FIG. 6 and further comprises an additional switch SW_0 connecting nodes A_1 and A_3 , controlled by a binary signal S_0 supplied by control unit 26. According to an embodiment, at previously-described step 55, in the second operating mode, in the absence of detection of a

dimmer, switch SW_0 is left permanently off. At previously-described step 54, in the first operating mode, when a dimmer is detected, switch SW_0 is turned on at the beginning and at the end of each cycle of voltage V_{ALIM} . According to an embodiment, unit 26 may control, at the beginning of a cycle of voltage V_{ALIM} , the turning off of switch SW_0 when the signal measured by sensor 28 exceeds a threshold, and control, at the end of a cycle of voltage V_{ALIM} , the turning on of switch SW_0 , while switch SW_1 is on, when the signal measured by sensor 28 decreases below a threshold. When switch SW_0 is turned on at the beginning and at the end of the cycle of voltage V_{ALIM} , a current may flow between input terminals IN_1 and IN_2 as soon as voltage V_{ALIM} is different from zero. Optoelectronic circuit 56 thus has a low input impedance between input terminals IN_1 and IN_2 at the beginning and at the end of the cycle of voltage V_{ALIM} . A dimmer connected to input terminals IN_1 and IN_2 can then operate properly.

According to an embodiment, current source 22 is a controllable current source and control unit 26 supplies a control signal COM to current source 22 in order to control the current source to modify the current supplied by current source 22 in the first operating mode. According to an embodiment, current source 22 may be controlled to supply a constant current for each cycle of voltage V_{ALIM} while a dimmer is detected.

FIG. 16 shows a more detailed electric diagram of an embodiment of an optoelectronic circuit 60. The elements common between optoelectronic circuit 60 and optoelectronic circuit 20 are designated with the same reference numerals.

Call V_{CS} the voltage across current source 22 and I_{CS} the current supplied by current source 22. Optoelectronic circuit 60 may comprise a circuit, not shown, for supplying a reference voltage to power current source 22, possibly obtained from voltage V_{ALIM} . For i varying from 1 to N , call V_{Ci} the voltage between the cathode of general light-emitting diode D_i and node A_2 . Further, voltage V_{ALIM} is also called V_{CO} . In the following description, unless otherwise mentioned, the voltages are referenced to node A_2 .

Optoelectronic circuit 60 further comprises $N+1$ comparison units $COMP_i$, with i varying from 0 to N , capable of each receiving voltage V_{Ci} and of supplying a signal H_i and a signal L_i . Control unit 26 receives signals L_0 to L_N and H_0 to H_N and supplies signals S_0 to S_N for controlling switches SW_0 to SW_N .

The elementary light-emitting diodes of each general light-emitting diode D_i , with i varying from 1 to N are, for example, planar light-emitting diodes, each comprising a stack of layers resting on a planar surface, having at least one active layer capable of emitting light. The elementary light-emitting diodes are, for example, planar light emitting diodes or light-emitting diodes formed from three-dimensional semiconductor elements, particularly microwires, nanowires, or pyramids, for example comprising a semiconductor material based on a compound mainly comprising at least one group-III element and one group-V element (for example, gallium nitride GaN), called III-V compound hereafter, or mainly comprising at least one group-II element and one group-VI element (for example, zinc oxide ZnO), called II-VI compound hereafter. Each three-dimensional semiconductor element is covered with at least one active layer capable of emitting light.

For i varying from 0 to N , switch SW_i is, for example, a switch based on at least one transistor, particularly a field-effect metal-oxide gate transistor or enrichment (normally on) or depletion (normally off) MOS transistor.

In the present embodiment, control unit 26 is capable of controlling the turning on or off of switches SW_i , with i varying from 0 to N , according to the value of voltage V_{Ci} . To achieve this, each comparison unit $COMP_i$, with i varying from 0 to N , is capable of comparing voltage V_{Ci} with at least two thresholds V_{high_i} and V_{low_i} . As an example, signal L_i is a binary signal which is in a first state when voltage V_{Ci} is smaller than threshold V_{low_i} and which is in a second state when voltage V_{Ci} is greater than threshold V_{low_i} . As an example, signal H_i is a binary signal which is in a first state when voltage V_{Ci} is smaller than threshold V_{high_i} and which is in a second state when voltage V_{Ci} is greater than threshold V_{high_i} . The first states of binary signals H_i and L_i may be equal or different and the second states of binary signals H_i and L_i may be equal or different.

FIG. 17 shows an electric diagram of a more detailed embodiment of a portion of electronic circuit 60. According to the present embodiment, each comparator $COMP_i$ comprises a first operational amplifier 62, operating as a comparator. The inverting input (−) of operational amplifier 62 is connected to the cathode of general light-emitting diode D_i , for i varying from 1 to N and to node A_1 for comparator $COMP_0$. The non-inverting input (+) of operational amplifier 62 receives voltage threshold V_{high_i} , which is supplied by a unit 64, which may comprise a memory. Operational amplifier 62 supplies signal H_i . Each comparator $COMP_i$ further comprises a second operational amplifier 66 operating as a comparator. The inverting input (−) of operational amplifier 66 is connected to the cathode of general light-emitting diode D_i , for i varying from 1 to N and to node A_1 for comparator $COMP_0$. The non-inverting input (+) of operational amplifier 66 receives voltage threshold V_{low_i} , which is supplied by a unit 68, which may comprise a memory. Operational amplifier 66 supplies signal L_i .

FIG. 18 shows an electric diagram of a more detailed embodiment of current source 22 and of switch SW_i . In the present embodiment, current source 22 comprises an ideal current source 70 having a terminal connected to a first source of a reference voltage VREF. The other terminal of current source 70 is connected to the drain of a diode-assembled N-channel MOS transistor 72. The source of MOS transistor 72 is connected to node A_2 . The gate of MOS transistor 72 is connected to the drain of MOS transistor 72. Reference potential VREF may be supplied from voltage V_{ALIM} . It may be constant or vary according to voltage V_{ALIM} . The intensity of the current supplied by current source 22 may be constant or be variable, for example, vary according to voltage V_{ALIM} .

For each general light-emitting diode D_i , current source 22 comprises an N-channel MOS transistor 74 having its gate connected to the gate of transistor 72 and having its source connected to node A_2 . MOS transistors 72 and 74 form a current mirror, current I_{CS} supplied by current source 70 being copied, possibly with a multiplication factor.

According to the present embodiment, switch SW_i comprises an N-channel MOS transistor 76 having its drain connected to the cathode of general light-emitting diode D_i and having its source connected to the drain of transistor 74. The voltage applied to the gate of transistor 76 corresponds to previously-described signal S_i .

FIG. 19 shows timing diagrams of power supply voltage V_{ALIM} , equal to voltage V_{CO} , and of the voltages V_{Ci} measured by each comparator $COMP_i$, with i varying from 1 to N , illustrating the operation of optoelectronic circuit 60 according to the embodiment shown in FIG. 16 in the case where N is equal to 4 and in the case where each general light-emitting diode D_i comprises the same number of

elementary light-emitting diodes arranged in the same configuration, and thus has the same threshold voltage V_{led} . As an example, voltage V_{ALIM} supplied by rectifying bridge 12 is a rectified sinusoidal voltage comprising a succession of cycles having voltage V_{ALIM} increasing from the zero value, crossing a maximum value, and decreasing to the zero value, in each of them. As an example, two successive cycles of voltage V_{ALIM} are shown in FIG. 19.

An embodiment will now be described for the second embodiment in the absence of detection of a dimmer. Call t_0 to t_{20} successive times.

At time t_0 , at the beginning of a cycle when a dimmer is not detected, switch SW_1 is turned on and all switches SW_i , with i varying from 2 to N , are turned off. Voltage V_{ALIM} rises from the zero value and distributes between general light-emitting diode D_1 , switch SW_1 , and current source 22. Voltage V_{ALIM} being smaller than threshold voltage V_{led} of general light-emitting diode D_1 , there is no light emission (phase P_0) and voltage V_{C1} remains substantially equal to zero.

At time t_1 , when the voltage across general light-emitting diode D_1 exceeds threshold voltage V_{led} , general light-emitting diode D_1 becomes conductive (phase P_1). The voltage across general light-emitting diode D_1 then remains substantially constant and voltage V_{C1} keeps on increasing along with voltage V_{ALIM} . As soon as power supply voltage V_{C1} is sufficiently high to allow the activation of current source 22, current I_{CS} flows through the general light-emitting diode D_1 which emits light. As an example, voltage V_{CS} , when current source 22 is in operation, is preferably substantially constant.

At time t_2 , when voltage V_{C1} exceeds threshold V_{high} , unit 26 successively controls the turning on of switch SW_2 and then the turning off of switch SW_1 . Voltage V_{ALIM} then distributes between general light-emitting diodes D_1 and D_2 , switch SW_2 , and current source 22. Preferably, threshold V_{high} is substantially equal to the sum of the threshold voltage of general light-emitting diode D_2 and of operating voltage V_{CS} of current source 22 so that, at the turning on of switch SW_2 , general light-emitting diode D_2 conducts current I_{CS} and emits light. The fact for switch SW_2 to be turned on before the turning off of switch SW_1 ensures that there will be no interruption of the current flow in general light-emitting diode D_1 . Phase P_2 corresponds to a phase of light emission by general light-emitting diodes D_1 and D_2 .

Generally, when a dimmer is not detected, during a rising phase of power supply voltage V_{ALIM} , for i varying from 1 to $N-1$, while switch SW_i is on and the other switches are off, unit 26 successively controls the turning on of switch SW_{i+1} and the turning off of switch SW_i when voltage V_{C1} exceeds threshold V_{high} . Voltage V_{ALIM} then distributes between general light-emitting diodes D_1 to D_{i+1} , switch SW_{i+1} , and current source 22. Preferably, threshold V_{high} is substantially equal to the sum of the threshold voltage of general light-emitting diode D_{i+1} and of operating voltage V_{CS} of current source 22 so that, at the turning on of switch SW_{i+1} , general light-emitting diode D_{i+1} conducts current I_{CS} and emits light. Phase P_{i+1} corresponds to the emission of light by general light-emitting diodes D_1 à D_{i+1} . The fact for switch SW_{i+1} to be turned on before the turning off of switch SW_i ensures that there will be no interruption of the current flow in general light-emitting diodes D_1 to D_i .

Thus, at time t_3 , unit 26 controls the turning on of switch SW_3 and the turning off of switch SW_2 . Phase P_3 corresponds to the emission of light by general light-emitting diodes D_1 , D_2 , and D_3 . At time t_4 , unit 26 controls the turning on of switch SW_4 and the turning off of switch SW_3 .

Phase P_4 corresponds to the emission of light by general light-emitting diodes D_1 , D_2 , D_3 , and D_4 .

Power supply voltage V_{ALIM} reaches its maximum value at time t_5 during phase P_4 in FIG. 19 and starts a falling phase.

At time t_6 , when voltage V_4 decreases below threshold V_{low} , unit 26 successively controls the turning on of switch SW_3 and the turning off of switch SW_4 . Voltage V_{ALIM} then distributes between general light-emitting diodes D_1 , D_2 , and D_3 , switch SW_3 , and current source 22. Preferably, threshold V_{low} is selected to be substantially equal to the sum of operating voltage V_{CS} of current source 22 and of the minimum operating voltage of switch SW_4 so that, at the turning on of switch SW_3 , there is no interruption of the current flow.

Generally, during a falling phase of power supply voltage V_{ALIM} , when a dimmer is not detected, for i varying from 2 to N , when voltage V_{C1} decreases below threshold V_{low} , unit 26 successively controls the turning on of switch SW_{i-1} and the turning off of switch SW_i . Voltage V_{ALIM} then distributes between general light-emitting diodes D_1 to D_{i-1} , switch SW_{i-1} , and current source 22. Preferably, threshold V_{low} is selected to be substantially equal to the sum of operating voltage V_{CS} of current source 22 and of the minimum operating voltage of switch SW_i so that, at the turning on of switch SW_{i-1} , there is no interruption of the current flow.

Thus, at time t_7 , unit 26 controls the turning on of switch SW_2 and the turning off of switch SW_3 . At time t_8 , unit 26 controls the turning on of switch SW_2 and the turning off of switch SW_1 . At time t_9 , voltage V_{C1} becomes zero so that general light-emitting diode D_1 is no longer conductive and current source 22 is off. At time t_{10} , voltage V_{ALIM} becomes zero and a new cycle starts. Times t_{11} to t_{20} are respectively similar to times t_1 to t_{10} . In the present embodiment, comparator $COMP_1$ may have a simpler structure than comparators $COMP_i$, with i varying from 2 to N , since threshold V_{low} is not used.

In the case where a leading edge dimmer is present, voltage V_{ALIM} is zero at the beginning of a cycle and then abruptly increases. During such an abrupt increase, at least two comparators $COMP_i$ and $COMP$ simultaneously switch signals H_i and H_j . If k is the highest index of comparator $COMP_k$ which switches signal H_k , control unit 26 successively controls the turning on of switch SW_{k+1} and then the turning off of all switches SW_0 to SW_k .

In the case where a trailing edge dimmer is present, voltage V_{ALIM} abruptly decreases during a cycle and then remains substantially zero until the end of the cycle. During such an abrupt decrease, at least two comparators $COMP_i$ and $COMP$ simultaneously switch signals L_i and L_j . If k is the highest index of comparator $COMP_k$ which switches signal L_k , control unit 26 successively controls the turning on of switch SW_{k-1} and then the turning off of all switches SW_{k+1} to SW_N .

In the first operating mode, when a dimmer is detected, switch SW_0 is turned on at the end and at the beginning of each cycle, for example, as long as the voltage across general light-emitting diode D_1 is smaller than threshold voltage V_{led} , the other switches being off.

In the first embodiment, control unit 26 may further control current source 22 as previously described.

According to another embodiment of optoelectronic circuit 60, each comparator $COMP_i$ of optoelectronic circuit 60 only supplies signal L_i . An advantage of this embodiment is

that the structure of comparator $COMP_i$ can be simplified. Indeed, it is possible for comparator $COMP_i$ not to comprise operational amplifier **62**.

The operation of the optoelectronic circuit according to this other embodiment is then identical to what has been previously described, with the difference that switches SW_i , with i varying from 0 to $N-1$ in the first embodiment, with i varying from 1 to $N-1$ in the second embodiment, are initially on and that, in a rising phase of power supply voltage V_{ALIM} , switch SW_{i-1} is turned off when voltage V_{Ci} becomes greater than threshold $Vlow_i$. Indeed, this means that current starts flowing through switch SW_i .

More specifically, in a rising phase of power supply voltage V_{ALIM} , while light-emitting diodes D_1 to D_{i-1} are conductive and light-emitting diodes D_i to D_N are off, when voltage V_{Ci} falls below threshold $Vlow_i$, unit **26** controls the turning off of SW_{i-1} . Indeed, a rise in voltage V_{Ci} means that the voltage across light-emitting diode D_i becomes greater than the threshold voltage of light-emitting diode D_i and that the latter becomes conductive.

The operation of the optoelectronic circuit according to this other embodiment in a falling phase of power supply voltage V_{ALIM} may be identical to that which has been previously described for optoelectronic circuit **60**.

FIG. **20** shows an electric diagram of another embodiment of an optoelectronic circuit **90**. All the elements common with optoelectronic circuit **60** are designated with the same reference numerals. Unlike optoelectronic circuit **60**, optoelectronic circuit **90** does not comprise switch SW_N . Further, unlike optoelectronic circuit **60**, for i varying from 1 to $N-1$, optoelectronic circuit **90** comprises a resistor R_i provided between node A_3 and switch SW_i , and optoelectronic circuit **90** comprises a resistor R_N provided between node A_3 and the cathode of general light-emitting diode D_N . Call B_i a node between resistor R_i and switch SW_i , for i varying from 1 to $N-1$, and B_N a node between resistor R_N and the cathode of general light-emitting diode D_N . Further, each comparator $COMP_i$, with i varying from 1 to N , further receives the voltage at node B_i . Signal H_i then is a binary signal which is in a first state when the voltage at node B_i is smaller than a threshold MIN_i and which is in a second state when the voltage at node B_i is greater than threshold MIN_i . A resistor R_0 may be provided in series with switch SW_0 .

Comparator $COMP_i$ and resistor R_i may be replaced with any device capable of determining whether a current greater than a current threshold flows through the branch comprising switch SW_i . According to an embodiment, a current mirror is arranged on the branch comprising SW_i to copy the current flowing through switch SW_i . The copied current can then be compared with a current threshold.

FIG. **21** shows an electric diagram of a more detailed embodiment of a portion of optoelectronic circuit **90**. In the present embodiment, comparator $COMP_i$ comprises all the elements of comparator $COMP_i$ shown in FIG. **17**, with the difference that operational amplifier **66** is replaced with a hysteresis comparator **92** receiving the voltage across resistor R_i and supplying signal H_i .

FIG. **22** shows an electric diagram of a more detailed embodiment of current source **22** and of switch SW_i for optoelectronic circuit **90**. Current source **22** comprises all the elements of the current source shown in FIG. **18**. Resistor R_i is interposed between MOS transistor **74** and node B_i , a terminal of resistor R_i being connected to the drain of transistor **74** and the other terminal of resistor R_i being connected to node B_i .

The operation of optoelectronic circuit **90** may be identical to the operation of previously-described optoelectronic

circuit **60** with the difference that, in a rising phase of power supply voltage V_{ALIM} , switch SW_i is turned off when current starts flowing through resistor R_{i+1} .

More specifically, switches SW_i , with i varying from 1 to $N-1$, are initially on, switch SW_0 being off in the second operating mode when a dimmer is not detected and being on in the first operating mode when a dimmer is detected. In a rising phase of power supply voltage V_{ALIM} , for i varying from 1 to $N-1$, while light-emitting diodes D_1 to D_{i-1} are conductive and light-emitting diodes D_i to D_N are off, when the voltage across light-emitting diode D_i becomes greater than the threshold voltage of light-emitting diode D_i , the latter becomes conductive and a current starts flowing through resistor R_i . This results in a rise in the voltage at node B_i . As soon as the voltage at node B_i rises above threshold MIN_i , unit **26** controls the turning on of switch SW_{i+1} .

The operation of optoelectronic circuit **90** in a falling phase of power supply voltage V_{ALIM} may be identical to that which has been previously described for optoelectronic circuit **60**.

Optoelectronic circuit **90** has the advantage that thresholds MIN_i and $Vlow_i$ can be independent from the characteristics of light-emitting diodes D_i . In particular, they do not depend on the threshold voltage of each light-emitting diode D_i .

Various embodiments with various variations have been described hereabove. It should be noted that those skilled in the art may combine various elements of these various embodiments and variations without showing any inventive step.

The invention claimed is:

1. An optoelectronic circuit intended to receive a variable voltage containing an alternation of rising and falling phases, the optoelectronic circuit comprising a plurality of light-emitting diode assemblies and a switching device capable of allowing or of interrupting the flowing of a current in each assembly, the switching device being further capable of detecting whether said variable voltage is supplied by a dimmer wherein the switching device is capable of connecting the assemblies of light-emitting diodes according to a plurality of connection configurations successively according to a first order during each rising phase of the variable voltage in the absence of a dimmer and a second order during each falling phase of the variable voltage in the absence of a dimmer, the switching device being further capable of detecting the presence of the dimmer when the duration of at least one connection configuration is shorter than a duration threshold and/or when at least two connection configurations follow each other according to a third order different from the first order and from the second order.

2. The optoelectronic circuit of claim 1, wherein the duration threshold depends on said at least one connection configuration.

3. The optoelectronic circuit of claim 1, wherein the switching device comprises at least one switch for each assembly of light-emitting diodes, the switching device being capable of transmitting binary control signals for the turning off or the turning on of the switches according to said connection configurations, the switching device being, further, capable of determining whether the duration between the successive switching times of one of two control signals of two successive connection configurations is shorter than said duration threshold.

4. The optoelectronic circuit of claim 1, wherein the switching device comprises, for each assembly, a compari-

son unit capable of comparing the voltage at one of the terminals of the assembly, and/or a voltage depending on said voltage at one of the terminals of the assembly, with at least one first voltage threshold and possibly with a second voltage threshold and a control unit connected to the comparison units and capable, during each rising phase, of interrupting the flowing of a current in each assembly from among certain assemblies of the plurality of assemblies when said voltage of said assembly rises above the second voltage threshold or when said voltage of the assembly, adjacent to said assembly and conducting the current, rises above the first voltage threshold and, during each falling phase, of controlling the flowing of a current in each assembly from among certain assemblies of the plurality of assemblies when said voltage of the assembly, adjacent to said assembly and conducting the current, decreases below the first voltage threshold.

5. The optoelectronic circuit of claim 4, wherein the switching device is capable of detecting the presence of the dimmer when, for at least two assemblies, the voltages associated with the two assemblies rise above the first voltage threshold or the second voltage threshold or fall below the first voltage threshold within a duration shorter than said duration threshold.

6. The optoelectronic circuit of claim 4, comprising a current source and, for each assembly, a switch connecting the current source to said terminal of said assembly, and wherein the control unit is capable, for each assembly from among certain assemblies of the plurality of assemblies, of controlling the turning on of the switch associated with said assembly when said voltage of the assembly, adjacent to said

assembly and conducting the current, falls below the first voltage threshold in each falling phase.

7. The optoelectronic circuit of claim 1, wherein the switching device is further capable of detecting whether the variable voltage is supplied by a leading edge dimmer or a trailing edge dimmer.

8. The optoelectronic circuit of claim 7, wherein the switching device is further capable of determining that the variable voltage is supplied by a leading edge dimmer when the duration of at least one connection configuration is shorter than a duration threshold during at least a rising phase of the variable voltage and/or when at least two connection configurations follow each other according to a fourth order different from the first order during at least a rising phase of the variable voltage and wherein the switching device is further capable of determining that the variable voltage is supplied by a trailing edge dimmer when the duration of at least one connection configuration is shorter than a duration threshold during at least one falling phase of the variable voltage and/or when at least two configuration connections follow each other according to a fifth order different from the second order during at least one falling phase of the variable voltage.

9. The optoelectronic circuit of claim 1, wherein the switching device is capable of at least temporarily decreasing an input impedance of the optoelectronic circuit when a dimmer is detected.

10. The optoelectronic circuit of claim 1, wherein the switching device is capable of having a constant current flow through the optoelectronic circuit when a dimmer is detected.
